CLAIM

The ornamental design for a cord retention device, as shown and described.

DESCRIPTION

FIG. 1 is a top view of a cord retention device showing my new design;

FIG. 2 is a front view thereof;

FIG. 3 is a bottom view thereof;

FIG. 4 is a rear view thereof;

FIG. 5 is a left side view thereof;

FIG. 6 is a right side view thereof;

FIG. 7 is a perspective view thereof; and,

FIG. 8 is an environmental view thereof.

The broken lines in the drawings represent unclaimed environmental subject matter.
